CLAIM

The ornamental design for a laptop bag part, as shown and described.

DESCRIPTION

FIG. 1 is a front perspective view of a laptop bag part;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a rear perspective view thereof.

The broken line showing of parts of the drawings depict environmental subject matter and form no part of the claim.
